PROTECTIVE CLOSURE MEANS FOR CONTAINERS

Filed Oct. 1, 1935

UNITED STATES PATENT OFFICE

2,094,961

PROTECTIVE CLOSURE MEANS FOR
CONTAINERS

Sante Quattrin, San Francisco, Calif.

Application October 1, 1935, Serial No. 42,993

5 Claims. (Cl. 215—14)

This invention relates to protective closure means for containers, such as bottles and the like.

An object of the invention is to provide a closure for containers, such as bottles or the like whereby refilling of the same is rendered difficult and wasteful unless the closure is mutilated or destroyed.

Another object of the invention is to provide means for preventing the refilling of bottles and like and particularly to provide lateral air and dispensing apertures or openings and means between said apertures which allow fluid to pass from the bottle out through the dispensing aperture, but when it is attempted to refill the bottle through either of said apertures, it causes the fluid to overflow out through the other aperture.

Another object of the invention is to facilitate the pouring of liquid out of a bottle or the like through a lateral opening, yet rendering any attempt to refill the bottle difficult and wasteful, and readily noticeable.

Another object of this invention is to provide closure means for containers and particularly for bottles which is highly useful and simple in construction. Convenience of arrangement, lightness and comparative inexpensive of manufacture are further objects which have been borne in mind in the production and development of the invention.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawing.

With the foregoing and other objects in view, which will be made manifest in the following detailed description and specifically pointed out in the appended claims, reference is had to the accompanying drawing for the illustrative embodiment of the invention, wherein:

Figure 1 is a sectional view of my closure shown on a fragmental, sectional view of a container outlet.

Figure 2 is a fragmental plan view of a usual flat bottle with my closure on it.

Figure 3 is a perspective view of a spilling element of my closure.

Figure 4 is a perspective view of a modified form of the spilling element.

Figure 5 is a face view of a circular dispensing aperture and spout on my device.

Figure 6 is a face view of a circular, divided dispensing aperture and spout on my device.

Figure 7 is a face view of a circular dispensing aperture with cross division.

Figure 8 is a face view of an elongated dispensing slot and spout.

Figure 9 is a sectional view of said elongated dispensing slot in my device.

Figure 10 is a face view of an elongated, and divided dispensing slot and spout.

Figure 11 is a face view of a rectangular dispensing aperture and spout.

Figure 12 is a fragmental, sectional view of the neck of a container, with my closure caps 20 and device thereon.

Figure 13 is a fragmental side view, partly in section of a modified form of my closure on a container.

Figure 14 is a sectional plan view of my closure or cap on a container.

In its general organization my invention includes opposed lateral apertures or openings 16 and 17, to form respectively an airvent and a dispensing aperture in the outlet or pouring end 30 of a container, such as the neck 18 of a bottle. The mouth 19 of the bottle is closed by a fixed closure wall which cannot be removed without mutilation, and after removal cannot be replaced unless by a difficult and costly manipulation, if at all. An obstruction element, such as a bar 21 is placed across the passage of the neck 18 so that a face 22 thereof is in alignment with the lowermost points of the apertures 16 and 17 at its ends.

The container or bottle is filled in the usual manner through its mouth then the bar 21 is inserted in place and the mouth is permanently covered, and sealed. To pour liquid out of the containers or bottle the same is tilted toward its dispensing aperture 17. The liquid passes by the bar 21 into the space above it and flows out through said dispensing aperture 17. In case of attempts to refill the container or bottle, without mutilating or removing the closure from its mouth, through either of the apertures 16 or 17, a great part, if not all of the liquid introduced from the outside into one aperture is directed by the face 22 of the bar 21 to the other, opposed

aperture, so as to cause the liquid to spill out of the bottle, instead of filling it.

In carrying out my invention in detail I provide a pair of opposed vertical grooves 23 extended from the mouth 19 over the inner ends of the respective apertures 16 and 17 to form opposed ledges 24 immediately adjacent the lower-most points or edges of the apertures 16 and 17. The grooves 23 are of such width as to slidably accommodate the bar 21 as it is inserted into the bottle. The bar 21 rests on the ledges 24 with its spilling face 22 in alignment with the lower portions of the apertures 16 and 17 and is held against lateral movements by the sides 15 of the grooves 23.

The bar 21 is preferably a flat strip of material, narrower than the width of the container outlet, or bottle neck 18, so as to allow the liquid to pass by the bar 21 into the space above it and 20 to the dispenser aperture 17 when the container or bottle is tilted. In the form shown in Figures 1, 3, and 4, the bar 21 has an upwardly extended flange 26 at its end adjacent the air vent opening 16 so as to practically cover the 25 inner end of said vent opening 16. The flange 26 has a perforation or hole 27 at its base fully aligned with the spilling surface 22 of the bar 21 so as to act as a small airvent as well as receive backflow from said spilling surface. It 30 is to be noted that the surface 22 will cause the greater part of the liquid introduced from outside of either aperture 16 or 17 to run along said surface and out through the other aperture instead of dripping down into the bottle, even 35 if the bottle is slightly tilted.

If desired a division pin 28 may be formed on the other end of the bar 21 adjacent the dispenser aperture 17 so as to reduce the normal inner area of the opening 17 and render the insertion of any filling tube still more difficult.

The bar 21 is wider than the width of the apertures 16 and 17 so as to prevent the insertion of any filling tube to either side of the bar 21. The flange 26 extends to the mouth of the neck 18 so 45 as to be engaged by the fixed closure wall thereat thereby to hold the bar 21 against vertical movement in the grooves 23. When a pin 28 is provided it also extends to the closure wall and functions also as an additional spacer for the 50 bar 21.

In the illustration shown in Figure 1, the apertures 16 and 17 are diametrically opposite each other through the sides of the bottle neck 18. The closure wall is formed by a cap 29 stamped and fixed into a preferably annular undercut 31 around the outside of the mouth 19 of the container outlet or bottle neck 18. If desirable the cap 29 may be cemented into said undercut 31. The cap 29 bears on its outside face the 55 trade-mark or other usual inscription of the original maker or filler, so as to allow easy recognition if the cap is ever replaced by unauthorized parties. Such replacement however is so difficult, if at all possible, that it renders any attempted refilling in such manner impractical and unprofitable in usual commercial practice.

The container outlet or bottle neck 18 is suitably threaded at 32 to detachably accommodate an outer cap 33 over the inner cap 29 and over the apertures 16 and 17. The outer cap 33 has a lining 34 of suitable compressible material, such as cork or rubber to fully seal the apertures 16 and 17 when not in use.

In the embodiment of my invention shown in Figure 12 the bottle neck 18 itself is not perfo-

rated, but into the undercut 31 is pressed and preferably cemented a fixed dispenser cap 36, the top 37 of which forms the fixed closure wall. The airvent aperture 16 and the opposed, dispenser aperture 17 are through the side of the 5 cap 36 and a spilling bar 38 extends across immediately below said apertures 16 and 17. A gasket of rubber or cork 39 is pinched under the securing flange 41 of the cap 36. This flange 41 also pinches and holds in place downwardly 10 and outwardly bent ears 42 of said bar 39. The entire cap 36 is covered by a removable outer cap 43 suitably lined to seal the apertures 16 and 17.

In the embodiment shown in Figure 13 the 15 spilling bar 44 is made integral with the dispenser cap 46, which latter in other respects is similar to the dispenser cap 36 herein before described.

In all of the embodiments of my invention the 20 dispenser aperture 17 may be made of various suitable shapes. The preferred shape of outlet aperture is illustrated in Figures 8 and 9, and it constitutes an elongated, narrow slot, preferably longitudinal relatively to the bottle neck 18. 25 Such slot provides a sufficiently large pouring area but it is too narrow to allow the insertion and manipulation of a filling tube or the like. The slot may be made wider as in Figure 10 and divided either by the pin 28 of the bar 21, 30 or formed with an integral partition. The aperture 17 may be of circular shape as in Figure 5, or divided circular shape, as in Figure 6, or cross divided circular shape as in Figure 7, or 35 rectangular as in Figure 11, the latter also either plain or divided.

In each instance an exterior spout 47 is formed around the outer end of the dispenser aperture 17 by a fluting, or indentation 48 into the outer surface of the material around aperture 17. The top portion of the spout 47 may be recessed as at 49, in Figure 8 and Figure 9, so as to provide a shortened lip from which the liquid after pouring, may drip back into the lower portion of the dispenser aperture 17. Such spout 47 and fluting or indentation 48, facilitate free pouring and eliminate back dripping to the outside of a container or bottle. The spout 47 is entirely within the plane of the outer surface of the neck 18 or 45 of the cap 36. In connection with flat bottles, such as in bottle 51 in Figure 2, it is preferable that the outlet aperture be to one side at an angle to the adjacent flat side of the bottle, in the direction where the bottle would be naturally 50 tilted for pouring by hand.

Having thus described my invention what I claim and desire to secure by Letters Patent is:

1. The combination with a bottle mouth provided with opposed dispensing and air openings and a permanent closure wall spaced from said openings, of a spout formed on the outer end of the dispensing opening, the outer surface of the bottle around said spout being grooved, said spout having a narrow slot longitudinal relatively to the bottle to form the outlet end of said dispensing opening, the edge of said slot nearer to said closure wall being recessed to form a shortened lip.

2. In a bottle the combination with a permanently fixed closure wall at the mouth of the bottle, and opposed lateral openings on the neck of the bottle, a flat plate narrower than the width of the interior of the neck of the bottle being extended between the openings so that the top level 75

of the plate is in alignment with the lowermost points of said openings.

3. In a bottle the combination with a permanently fixed closure wall at the mouth of the bottle, and opposed lateral openings on the neck of the bottle, a flat plate narrower than the width of the interior of the neck of the bottle being extended between the openings so that the top level of the plate is in alignment with the lowermost 5 points of said openings, and a member extended from one end of said plate toward said closure wall so as to cover the adjacent opening, said member being perforated.

4. In a bottle the combination with a permanently fixed closure wall at the mouth of the bottle, and opposed lateral openings on the neck of the bottle, a flat plate narrower than the width of the interior of the neck of the bottle being extended between the openings so that the top level 10 of the plate is in alignment with the lowermost 15 points of said openings, said bottle neck having

grooves extended from the mouth of the bottle to a point immediately below each opening to hold said plate against lateral displacement.

5. In a bottle the combination with a permanently fixed closure wall at the mouth of the bottle, and opposed lateral openings on the neck of the bottle, a flat plate narrower than the width of the interior of the neck of the bottle being extended between the openings so that the top level of the plate is in alignment with the lowermost 5 points of said openings, said bottle neck having grooves extended from the mouth of the bottle to a point immediately below each 10 opening to hold said plate against lateral displacement, a perforate member extended from one end of the plate to the closure over the adjacent opening, and a division extension extended from the other end of the plate to said closure 15 to cover a portion of the other opening, the latter opening being the outlet opening. 20
